UNITED STATES PATENT OFFICE

WILLIAM J. DE WITT, OF AUBURN, NEW YORK, ASSIGNOR TO SHOE FORM CO., INC., OF AUBURN, NEW YORK, A CORPORATION OF NEW YORK

SHOE FORM

Application filed April 25, 1929. Serial No. 357,947.

This invention relates to an improvement in shoe forms more particularly in shoe forms of resilient material comprising a hollow toe member and a cross bar by which the walls 5 of the toe member may be expanded or contracted. It is desirable in shoe forms of this type that means be provided whereby the same form may be used for a plurality of widths of shoes and that such means include 10 holding or limiting elements so that the form may be set to any desired width and when so set will remain in that position.

The primary object of this invention is to provide such a shoe form, comprising a toe 15 member and a cross bar, with means whereby the position of the cross bar and the consequent width of the form can be definitely set and furthermore whereby the particular width of any shoe can be readily determined 20 by an inspection of the shoe form.

A further object of the invention is to provide means whereby the toe member may be set to any definite width or may be expanded or contracted without the necessity of expanding or contracting the member at any 25 time beyond a certain predetermined limit, the increase or decrease in width being at all times a gradual operation. In this connection it may be noted that shoe forms having this 30 general purpose have been previously made but, the operation of increasing or decreasing the width of the toe member can not be performed while in a shoe since the toe member must be expanded beyond its normal limits as 35 its width is increased or decreased, an expansion that would be resisted by the walls of the shoe.

In the accompanying drawings are illustrated 40 several embodiments of this invention in which drawings:

Fig. 1 is a bottom plan view of a shoe form illustrating one embodiment of this invention in which the walls may be increased or decreased 45 in width, the position of the walls of the member when in the contracted position being indicated in full lines and when in expanded position being indicated in dotted lines;

Fig. 2 is a view similar in all respects to

Fig. 1 illustrating another embodiment of this invention;

Fig. 3 is a sectional view taken along the line 3—3 of Fig. 1;

Fig. 4 is a sectional view taken along the 55 line 4—4 of Fig. 3;

Fig. 5 is a sectional view taken along the line 5—5 of Fig. 2;

Fig. 6 is a sectional view taken along the 60 line 6—6 of Fig. 5;

Fig. 7 is a fragmentary plan view of a shoe 65 form illustrating another embodiment of this invention; and

Fig. 8 is a sectional view thereof taken along the line 8—8 of Fig. 7.

Referring to the embodiment illustrated in Figs. 1, 3 and 4 the reference numeral 10 indicates a toe member the walls of which are connected by a cross bar 11 which acts to expand or contract the walls and to hold them 70 in the desired relation to each other. One side wall of the toe member terminates in a flange 15 and the opposite side wall in a corresponding flange 16. In the flange 16 is formed a curved or arcuate slot 17 and a portion 18 of the edge of the flange 16 outside and beside the slot 17 is upset or turned up and provided with a series of pockets 19. The pockets 19 in the present instance are formed by cutting notches in the edge of the upturned 75 portion 18.

The cross bar 11 is pivotally secured at one end to the flange 15 in any suitable manner as by a rivet 20. The other end of the cross bar 11 is attached to a button 21 within the slot 17, the ends of the button being expanded 85 at 22 and 23 to insure that the button is held within the slot and to facilitate the connection of the cross bar thereto. The cross bar, thus secured at one end to the rivet 20 and at the other end to the button 21, extends over the upset portion 18 of the flange 16 and normally rests in one of the pockets 19. (See Fig. 4.)

The pockets 19 hold the cross bar 11 in any desired position and determine the width of the toe member 10. Obviously the particular pocket in which the cross bar 11 rests indicates a width of the toe member and conse- 95 100

quently the width of the shoe with which such toe member cooperates.

The embodiment shown in Figures 2, 5 and 6 comprises a toe member 30 and a cross bar 31, the side walls of the toe member 30 terminating in flanges 35, 36 and the flange 36 being provided with a slot 37. Between the inner edge of the flange 36 and the slot 37 the material is upset to form a plurality of bosses 38 spaced apart to provide pockets 39. The cross bar 31 is pivotally secured to the flange 35 by suitable means, such as a rivet 40, and is attached to a button 41 in the slot 37 having expanded ends 42, 43. The cross bar 31 extends over the pockets 39 which are arranged to receive the cross bar and hold it yieldingly in any desired position.

The pockets 39 of this embodiment function as holding or limiting means in the same way as do the pockets 19 of the other embodiment and the operation and purpose of this second embodiment is the same as that of the first embodiment.

Thus the upset portions defining a pocket 25 present resistance to the pivotal movement of the cross bar as it leaves the pocket.

The embodiment shown in Figs. 7 and 8 is similar to that shown in Figs. 2, 5 and 6 differing therefrom in the contour of the upset 30 bosses provided in the flange 36' between the slot 37' and the inner edge thereof. The bosses 45 of this embodiment are elongated thus providing longitudinally extending pockets 46 which receive the cross bar 31' and 35 yieldingly resist its pivotal movement. The bosses 45 preferably diverge outwardly, the pockets 46 being on radii from the rivet as a center, and may, if desired, terminate short of the edge.

40 The guiding means of each embodiment comprise an arcuate slot and a guide member, which is shown in each as a button. The guide member is attached to one end of the cross bar and thus the guiding means provide a sliding engagement between the cross bar and one flange of the toe member.

Moreover it will be noted that in each embodiment the movement of the cross bar in expanding or contracting the toe member is smooth, continuous and uninterrupted, the holding or limiting means associated with the slotted flange offering merely a yielding resistance to the movement of the cross bar. Such means raise the cross bar vertically but 50 do not cause any longitudinal or horizontal movement thereof and in no way affect the expanding or contracting movement of the walls of the toe member. Hence the cross bar may be shifted while within the shoe without imposing any undue strain thereon, whereas in the type previously known this is not the case. It is accordingly necessary to set the form of the previously known type at the desired width before inserting it in the 55 shoe while a form embodying this invention

may be inserted in the shoe in its most contracted position and later expanded smoothly and continuously to the desired amount, the reaching of which can be easily ascertained by noting the pocket by which the movement of the cross bar is yieldingly resisted. 70

While three embodiments only have been shown and described I am not limited thereto since other embodiments can be made without departing from the spirit and scope of invention set forth in the following claims: 75

1. A shoe form comprising a hollow toe member of resilient material, a cross bar pivotally attached at one end to one wall of the toe member and guiding means associated with the opposite wall of the member and with the other end of the cross bar whereby the pivotal movement of the cross bar causes the width of the toe member to increase or decrease, and a plurality of means independent 80 of the guiding means for engaging the cross bar and resisting its pivotal movement and the consequent change in the width of the toe member.

2. A shoe form comprising a hollow toe member of resilient material, a cross bar pivotally attached at one end to one wall of the toe member and guiding means associated with the opposite wall of the member and with the other end of the cross bar whereby the pivotal movement of the cross bar causes the width of the toe member to increase or decrease, and a plurality of means independent 90 of the guiding means for engaging the cross bar and yieldably resisting its further 95 pivotal movement in either direction and the consequent increase or decrease in the width of the toe member.

3. A shoe form comprising a hollow toe member of resilient material, a cross bar pivotally attached at one end to one wall of the toe member and guiding means associated with the opposite wall of the member and with the other end of the cross bar whereby the pivotal movement of the cross bar causes 100 the width of the toe member to increase or decrease, and a plurality of means associated with one wall of the toe member and independent of the guiding means for engaging the cross bar and resisting its pivotal movement and the consequent change in the width of the toe member. 105

4. A shoe form comprising a hollow toe member of resilient material, a cross bar pivotally attached at one end to one wall of the toe member and guiding means associated with the opposite wall of the member and with the other end of the cross bar whereby the pivotal movement of the cross bar causes the width of the toe member to increase or 110 decrease, and a plurality of means associated with the wall of the toe member with which the guiding means is associated and independent of such means for engaging the cross bar and resisting its pivotal movement and 115 120 125 130

the consequent change in the width of the toe member.

5. A shoe form comprising a hollow toe member of resilient material the walls of which are flanged, one flange having a slot therein, a cross bar pivoted at one end to the other flange, and a guide member in said slot to which the other end of the cross bar is secured, whereby upon the pivotal movement of the cross bar the guide member is moved in the slot and the width of the toe member increased or diminished, and a plurality of means independent of the slot for holding the cross bar stationary and the toe member at any of several predetermined widths.

6. A shoe form comprising a hollow toe member of resilient material the walls of which are flanged, one flange having a slot therein, a cross bar pivoted at one end to the other flange, and a guide member in said slot to which the other end of the cross bar is secured, whereby upon the pivotal movement of the cross bar the guide member is moved in the slot and the width of the toe member increased or diminished, and a plurality of means independent of the slot which pockets engage the cross bar and thereby yieldingly prevent a change in the width of the toe member.

7. A shoe form comprising a hollow toe member of resilient material, the walls of the toe member being flanged, a series of pockets associated with one of the flanges, a cross bar pivotally secured to the other of the flanges and guiding means independent of said pockets, which means upon the pivotal movement of the cross bar provide a sliding engagement between the cross bar and the pockets-associated flange, each of said pockets being adapted to receive said cross bar and hold it yieldingly in a predetermined position.

8. A shoe form comprising a hollow toe member of resilient material, the walls of the toe member being flanged, a series of pockets associated with one of the flanges, a cross bar pivotally secured to the other of the flanges, said pockets-associated flange being provided with guiding means independent of the pockets, and including a movable guiding member to which member said cross bar is attached whereby a sliding engagement between the cross bar and the flange is provided, each of said pockets being adapted to receive said cross bar and hold the movable guiding member in a predetermined position.

9. A shoe form comprising a hollow toe member of resilient material, the walls of the member being flanged, one of said flanges having a curved guiding slot therein, a cross bar pivoted at one end to the other of said flanges, a guiding member movable in said slot and associated with the cross bar whereby upon the pivotal movement of the cross

bar the member is moved in the slot and the width of the toe member increased or diminished and means associated with said slotted flange and independent of said slot with which means the cross bar engages to hold the toe member at the width determined by the pivotal movement of the cross bar.

10. A shoe form comprising a hollow toe member of resilient material, the walls of the member being flanged, one of said flanges having a curved guiding slot therein, a cross bar pivoted at one end to the other of said flanges, a button movable in the slot and attached to the other end of the cross bar whereby upon the pivotal movement of the cross bar the button is moved in the slot and the width of the toe member increased or diminished and a series of pockets on the slotted flange and independent of the slot which pockets engage the cross bar and thereby yieldingly prevent a change in the width of the toe member.

11. A shoe form comprising a hollow toe member of resilient material, the walls of the member being flanged, one of said flanges having a curved guiding slot therein, a cross bar pivoted at one end to the other of said flanges, a button movable in the slot and attached to the other end of the cross bar whereby upon the pivotal movement of the cross bar the button is moved in the slot and the width of the toe member increased or diminished, and a series of pockets formed in the slotted flange, adjacent to but independent of the slot which pockets engage the cross bar to hold the toe member against any change in width.

12. A shoe form comprising a hollow toe member of resilient material, the walls of the member being flanged, one of said flanges having a curved guiding slot therein, a cross bar pivoted at one end to the other of said flanges, a button movable in the slot and attached to the other end of the cross bar whereby upon the pivotal movement of the cross bar the button is moved in the slot and the width of the toe member increased or diminished and a series of pockets intermediate the ends of the cross bar and independent of the slot which pockets are adapted to engage the cross bar during its pivotal movement and yieldingly prevent a change in the width of the toe member.

Signed by me at Auburn, N. Y. this 18th day of April, 1929.

WILLIAM J. DE WITT.
